UNITED STATES PATENT OFFICE.

CLARENCE S. MARCO, OF CHICAGO, ILLINOIS.

COUPON-SHEET.

1,258,922.

Specification of Letters Patent. Patented Mar. 12, 1918.

Application filed September 9, 1916. Serial No. 119,158.

To all whom it may concern:

Be it known that I, CLARENCE S. MARCO, a citizen of the United States of America, and resident of Chicago, Cook county, 5 Illinois, have invented a certain new and useful Improvement in Coupon-Sheets, of which the following is a specification.

My invention relates to coupon-sheets for use in the work-rooms of clothing factories, 10 or in other places where coupons for piece-work are given the employees, and in which it is desirable to provide means for holding the coupons together and facilitating the computing of the total value thereof.

15 The object of my invention is, therefore, to provide a coupon-sheet having means for indicating the cumulative or total value of all the coupons so far attached thereto, so that a glance at the sheet will show the 20 entire value of all the coupons thereon.

It is also an object to provide certain details and novel features and combinations tending to increase the general efficiency and desirability of a coupon-sheet of this 25 particular character.

To the foregoing and other useful ends, my invention consists in matters hereinafter set forth and claimed.

In the accompanying drawings:—
30 Figure 1 is a face view of a coupon-sheet embodying the principles of my invention.

Fig. 2 shows one of the coupons which are to be attached to the sheet.

As thus illustrated, my invention comprises a rectangular sheet of paper or other material A having the surface thereof divided into five vertical columns by the vertical lines a, and each column divided into spaces by the horizontal lines 1. At the top 35 of the sheet is a space 2 with numerals indicating the value or denomination of each coupon to be attached. The top of the coupon is also provided with means for indicating the method of attaching the coupons, as shown in the drawing, and with 40 spaces for the number and name of each employee, and the particular shop. The space at the top of each column has printed therein the necessary instructions for attaching 45 the first coupon of each column. For example, the first coupon for the first column is attached in the first space, the second in the space directly below, the third in the next space, and so on to the bottom of the 50 column. The coupons are attached in the other columns in a similar manner. With 55

the exception of the uppermost space of each column, the different spaces are all subdivided by vertical lines 3, so that each space is divided into 3 sub-sections which are each 60 substantially square in shape. In the upper left-hand corner of each sub-section is a numeral, the first or left-hand sub-section of each space being numbered 1, the next one 2, and the last or right-hand sub-section being 65 numbered 3, so that the number 1 sub-sections are all in a vertical line, and the number 2 sub-sections all in a vertical line, and the number 3 sub-sections all in a vertical line, in each column of spaces, in the manner 70 shown in the drawing. As the first coupon, which has a value of $.01\frac{1}{4}$, is attached to the uppermost space in the first column, it follows that the first or left-hand sub-section of the second space, which is the 75 next space just below the coupon, bears the indication $.01\frac{1}{4}$, so that if only one coupon has been attached, and if this is the first sheet, a glance at the left-hand sub-section just below the coupon will instantly show 80 the value of the sheet thus far. When the second coupon is attached to the second space, the total value will be $.03\frac{1}{4}$, so that the first or left-hand sub-section in the third space has printed thereon $.03\frac{1}{4}$, so 85 that a glance at the indication just below the second coupon will show the total value of the sheet to date. It will be seen that the sub-sections in this vertical column all have similar indications printed thereon, the 90 value increasing $.01\frac{1}{4}$ for each successive sub-section in a downward direction, so that the lowermost sub-section bears the indication $.15\frac{1}{4}$. When a coupon is attached to this last or tenth space, the total value will 95 be $.17\frac{1}{2}$, so that to indicate this cumulative value of the ten coupons the indicating figure $.17\frac{1}{2}$ is printed immediately below the No. 1 column of sub-sections, and the space in which this is printed is also numbered 1, 100 while the next space is numbered 2, and the third is numbered 3, these spaces being in line with the three vertical columns of sub-sections. The eleventh coupon is then attached at the top of the second column, in 105 the first space, as indicated by the directions printed thereon. The cumulative value of all the coupons is then $.19\frac{1}{4}$, as indicated by the figure printed in the first or left-hand sub-section immediately below. It will 110 be seen that all five columns of the sheet are thus provided with figures indicating the

22
 cumulative value of the coupons, so that whenever each space is occupied by a coupon the total value thereof will be $.87\frac{1}{2}$, which is indicated below the last sub-section of the first column of sub-sections in the fifth or right-hand column of spaces. Each column of spaces has its three total-value indicating spaces immediately below and numbered 1, 2, 3, as shown in the drawing. When the final coupon is attached, a glance at the sheet shows, without stopping to count the number of coupons, or the number of spaces, or anything else, that the total or cumulative value of all the coupons attached is $.87\frac{1}{2}$, as shown in the drawing, thereby greatly facilitating the work of determining the value of piece-work done by the employee.

Now it may occur that one sheet will not be sufficient, and that in order to total all the coupons issued to an employe two sheets and sometimes three sheets will be necessary. It is for this reason that the five vertical columns of spaces are each divided into three sub-columns by the vertical lines 3, and each sub-column numbered 1 or 2 or 3 as the case may be. In this way, if the sheet shown is supposed to be the second sheet which is being filled in with coupons by the employe, then the attachment of the first coupon, at the top of the first column, will immediately show, by the indication printed in the middle or second sub-section immediately below, that the total value of the two sheets is $.89\frac{1}{2}$; and, on the other hand, if the sheet shown in the drawings is the third sheet to be filled with coupons by the employe, then the first coupon attached at the top of the first column will immediately show a total value of all three sheets of $1.76\frac{3}{4}$, by the indication in the third sub-section of the second space in the first column. When two sheets are entirely filled, the total or cumulative value will be 1.75, as indicated by the middle space below the bottom of the last column. On the other hand, if three sheets have been filled, the total value will be indicated on the third sheet at the bottom of the column, and will be $\$2.62\frac{1}{2}$, as shown in the drawing. Thus which sub-columns of each column of the sheet are used, in reckoning the total or cumulative value of the coupons, depends upon whether the sheet is the first or the second or the third. The sheets are all printed alike, but they can be used separately, or two sheets can be used together, or three sheets can be used together. If only two sheets are to be used together, the second sub-column of each column of spaces is used, and if three sheets are to be used then the third sub-column of each column of spaces is used.

In any event, therefore, as shown, regardless of whether the sheet is printed with sub-columns for the different vertical columns of spaces, the figure immediately below the last

coupon will always indicate the cumulative value of all the coupons so far attached.

For the attachment of the coupons, any suitable or known expedient can be used. For example, the entire surface of the coupon-sheet A can be given a thin coating of mucilage or other adhesive, so that a slight wetting or dampening of the coupon will enable it to adhere to the desired place on the sheet. 75

The coupons B may be of any suitable form, such as that shown in Fig. 2, and they may be of any suitable material. It will be understood, of course, that the coupons must be of a size to fit within the spaces formed by the lines a and b, as indicated in dotted lines in Fig. 1. 80

It will also be seen that the direct indication of the total or cumulative value of all the coupons, each time another coupon is attached, does not necessarily have any relation to the number of coupons. Thus, coupons having fractional values can be easily handled, and the number of coupons attached to the sheet is unimportant, as regardless of what the number may happen to be the total or cumulative value thereof is at once apparent. And by directly indicating the total value of all the coupons, after each coupon, no addition or subtraction or other computing will be necessary, as the cumulative value is always accurately stated after the last coupon. 90

It will be understood, of course, that the sheets can be printed for any particular or desired value of coupon, and that each sheet may also be divided and sub-divided so that either two or three or four or five or any other number of sheets can be used in conjunction with each other. In other words, 105 each coupon-space can be subdivided into any desired number of sub-sections or smaller spaces.

What I claim as my invention is:—

1. A coupon-sheet having spaces thereon for the successive attachment of the coupons, and having permanent means thereon for directly indicating after the attachment of each coupon and adjacent thereto the exact total value of all coupons thus far attached, 110 so that only coupons of a certain value each can be used on said sheet, and coupons of said value for attachment to said sheet, said spaces being arranged in vertical columns and each column being divided into sub-columns, with as many sub-columns for each main column as there are sheets necessary for the maximum number of sheets to be used in conjunction with each other. 120

2. The said coupon-sheet, as specified in 125 claim 1, each sub-column containing figures to indicate the cumulative value of all the coupons thus far attached on either one or more sheets.

3. A coupon-sheet having spaces thereon 130

for the successive attachment of the coupons, and having permanent means thereon except in the space for the first coupon for directly indicating by cumulative amounts which 5 are visible after the attachment of each coupon and adjacent thereto the exact total value of all coupons thus far attached, so that only coupons of a certain value each can be used on said sheet, and separate coupons of said value for permanent attachment 10 to said sheet, one coupon to each space whereby the sheet when either fully or partially completed by the permanent attachment of said coupons always has the exact 15 total value thereof left exposed adjacent the last coupon.

4. A coupon-sheet having spaces thereon for the successive attachment of the coupons, and having permanent means thereon, 20 except in the space at the top of the sheet for directly indicating by cumulative amounts which are visible after the attachment of each coupon and adjacent thereto the exact total value of all coupons thus far 25 attached, so that only coupons of a certain value each can be used on said sheet, and separate coupons of said value for permanent attachment to said sheet, said means consisting of figures of such constantly increasing 30 value and which are so placed on said sheet that the figure immediately below the last coupon is always the exact total value of all the coupons on the sheet, whereby the sheet when either fully or partially completed by 35 the permanent attachment of said coupons always has the exact total value thereof left exposed adjacent the last coupon.

5. A coupon-sheet having spaces thereon for the successive attachment of the coupons, 40 and having permanent means thereon for directly indicating by cumulative amounts which are visible after the attachment of each coupon and adjacent thereto the exact total value of all coupons thus far attached, 45 so that only coupons of a certain value each can be used on said sheet, and separate coupons of said value for permanent attachment to said sheet, said means consisting of figures of such value and so placed on the sheet

that the figure immediately below the last 50 coupon shows the cumulative value of all the coupons, said spaces being arranged in vertical columns, with said means in all spaces except the first space of each column and some of said figures being below the last 55 space in each column, so that the total of each column is always visible at the bottom thereof, before the sheet is finished, and whereby the sheet when fully completed by the permanent attachment of said coupons 60 has the total of each column left exposed.

6. A coupon-sheet having spaces thereon arranged in vertical columns, means on the sheet to indicate the denomination of the coupon to be used, coupons of said denomination for permanent attachment in said spaces, means in all of the spaces, except the space at the head of each column, to indicate the total value of the coupons attached, so that the total or cumulative amount 70 always appears immediately below the last coupon, with the totals of said columns below the bottom line of the columns, the total for each column including the total or totals of any previous column or columns, whereby 75 the total of the last column is the total value of the sheet, and the first space of each column having means to show which coupon belongs therein.

7. The said coupon-sheet and coupons 80 therefor, as stated in claim 6, in which said spaces, except the first space of each column, are provided with means to indicate the cumulative value of said coupons plus the coupons on any previous sheet. 85

8. The said coupon-sheet and coupons therefor, as stated in claim 6, in which said spaces have adhesive surface for moistening to receive the coupons.

9. The said coupon-sheet and coupons 90 therefor, as stated in claim 6, in which said sheet has means to indicate the cumulative value of said coupons plus the coupons of any previous sheet.

Signed by me at Chicago, Illinois, this 95
30th day of August, 1916.
